UNITED STATES PATENT OFFICE.

ALFRED R. MORRILL, OF BEVERLY, MASSACHUSETTS, ASSIGNOR, BY MESNE ASSIGNMENTS, TO UNITED SHOE MACHINERY CORPORATION, OF PATERSON, NEW JERSEY, A CORPORATION OF NEW JERSEY.

THREAD-WAXING DEVICE.

1,333,766.

Specification of Letters Patent. Patented Mar. 16, 1920.

Application filed May 22, 1917. Serial No. 170,313.

To all whom it may concern:

Be it known that I, ALFRED R. MORRILL, a citizen of the United States, residing at Beverly, in the county of Essex and State 5 of Massachusetts, have invented certain new and useful Improvements in Thread-Waxing Devices; and I do hereby declare the following to be a full, clear, and exact description of the invention, such as will enable others skilled in the art to which it 10 appertains to make and use the same.

This invention relates to thread-waxing devices for applying melted wax to sewing thread.

15 The objects of the invention are to improve the construction and arrangement of the parts of thread-waxing devices, and to produce a thread-waxing device having thread guiding devices for guiding the 20 thread through the wax in the receptacle, mounted in an improved manner so that these devices may be readily threaded.

25 With these objects in view the invention consists in the novel and improved constructions and arrangements and combinations of parts hereinafter described and particularly pointed out in the claims.

30 The invention will be readily understood from the accompanying drawings illustrating a thread-waxing device embodying the features of the invention in their preferred forms, and the following detailed description of the constructions 35 therein shown.

35 In the drawings, Figure 1 is a plan view of a thread-waxing device embodying the invention; Fig. 2 is a view in side elevation of the thread-waxing device; Fig. 3 is a view in front elevation of the thread-waxing 40 device, with a portion of the receptacle broken away; Fig. 4 is a view in horizontal section of the device taken substantially on the line 4-4 of Fig. 3; and Fig. 5 is a detail view, partly in plan and partly in horizontal section, illustrating the construction for holding the rotatable thread 45 guide support in position.

50 In the construction illustrated in the drawings, the thread-waxing device comprises a wax receptacle 2 having an arm 4 for securing the receptacle to the frame of a sewing machine, or to any other suitable support. In this construction the wax re-

ceptacle is arranged to be heated by steam or other fluid heating medium. The heating mechanism comprises a pipe 6 threaded at its lower end into the base of the wax receptacle and held securely in place by a lock nut 8. A second pipe 10, somewhat smaller than the pipe 6, is passed through the latter pipe, as shown particularly in Figs. 2 and 4. To the upper end of the pipe 10 is secured a bracket or block 12, having a passageway 14 in communication with the passageway in the pipe 10. The bracket 12 is formed with a flange 16 which engages the upper end of the pipe 6, and a nut 18 threaded upon the lower end of the pipe 10 engages the lower end of the pipe 6 to secure the pipe 10 and the bracket in position. The lower end of the pipe 10 is adapted to be connected with the supply pipe of any suitable steam heating system, and an outlet pipe 20 secured at one end to the bracket 12 communicates with the passageway 14 in the bracket. The inner pipe 10 is considerably smaller than the outer pipe 6, so that an air space is left between the two pipes, as shown in Fig. 4. The pipe 10 is preferably made of brass, while the outer pipe 6 is preferably made of iron. The pipe 6 forms a jacket for the inner pipe 10 to keep the melted wax out of contact with the latter pipe. The arrangement of the jacket pipe 6 with an air space between the same and the heating pipe 10 eliminates to a great degree the danger of burning or overheating the wax in the receptacle. The making of the outer jacket pipe of iron, the coefficient of conductivity of which is much less than that of brass, constitutes a further feature tending to prevent overheating or burning of the wax. The receptacle 2 is formed with a mouth 21, into which the lumps of unmelted wax are introduced in supplying the receptacle with wax. By the heat transmitted by the steam or other heating medium circulating through the pipe 10, the wax in the receptacle 2 is maintained in a suitable melted condition to be applied to a thread passed through the receptacle.

In applying the melted wax to the thread, the thread is immersed in the melted wax in the receptacle so that it will thoroughly impregnate the thread. The guides for determining the path of the thread as it passes

through the receptacle are arranged so that the thread travels through the receptacle in a path fairly close to the pipe 6, where the wax is maintained in a thoroughly melted condition. In the present construction two sets of thread guides are provided, one for the needle thread of the sewing machine, to which the thread-waxing device is applied, and the other for the thread to be wound upon the bobbins of the machine. In the drawings the two threads are indicated respectively by the reference characters A and B. The thread A enters the receptacle through an opening 22 in a circular plate 24, forming a part of the cover of the receptacle, thence passes downwardly into the receptacle, through a porcelain thread-eye 26, and from the thread-eye passes upwardly through a stripping device 28 mounted on the plate 24. After passing through the stripping device, the thread passes about the thread trucks 30 and 32, mounted upon a bracket 34 secured to the bracket 12. The thread B enters the receptacle through an opening 36 in the plate 24, thence passes downwardly into the receptacle, through a porcelain thread-eye 38, and then passes upwardly through a stripping device 39, mounted on the plate 24. To enable the thread-eyes 26 and 38 to be threaded readily, both of the thread-eyes are mounted so that they may be easily removed from the receptacle to permit the threads to be passed through the same. In the construction shown, the thread-eye 26 is secured by means of a U-shaped yoke 40 to the lower end of a carrier bar 42 mounted on the plate 24. The bar 42 is secured in a notch 44 in the plate 24 by means of a screw 46. The bar is formed with an opening 48 slightly larger than the head of the screw 46, and with a relatively narrow slot 50 connected with the opening 48 and adapted to receive the shank of the screw. The drawings show the bar 42 secured in position on the plate 24, the shank of the screw 46 passing through the slot 50, and the bar being held in position on the plate by the engagement of the head of the screw therewith. The bar, however, may be readily removed from the plate by first loosening the screw 46 slightly, then moving the bar upwardly until the opening 48 registers with the head of the screw, and moving the upper end of the bar outwardly to disengage the screw from the opening. The bar can then be lifted to remove the thread-eye 26 from the wax so that the thread can be passed through the eye. The thread-eye 38 is mounted in the same manner as the thread-eye 26. The thread-eye 38 is secured by means of a yoke 52 to the lower end of a carrier bar 54 secured at its upper end in a notch 56 in the plate 24 by means of a screw 58. The bar 54 is formed with an opening 60 somewhat larger than

the head of the screw 58, and with a slot 62 connected with the opening and adapted to receive the shank of the screw.

The plate 24 is illustrated in the drawings in its normal position. It will be noted that with the plate in the position shown, the bar 42 is opposite the mouth 21 of the wax receptacle, so that the bar can be readily removed from the plate. The bar 54, however, is located upon the portion of the plate 75 remote from the mouth of the receptacle, where the wall of the receptacle lies close to the bar, so that the bar cannot be detached from the plate 24 and the bar and thread eye 38 removed from the receptacle. 80 In order to permit either the bar 42 or the bar 54 to be detached from the plate 24 and removed with its attached thread eye from the receptacle, the plate 24 is rotatably mounted upon the upper end of the pipe 6. 85 This manner of mounting the plate enables the plate to be turned so as to place either the bar 42 or the bar 54 in a position opposite the mouth of the receptacle, so that it can be readily detached from the plate, and 90 the bar and the thread-eye mounted thereon removed from the receptacle. The plate 24 is held in the position shown in the drawings by means of a thumb-nut 64 threaded upon a screw 66 mounted in a lateral projection 68 on the receptacle, the lower reduced portion of the nut engaging in a recess 70 in the plate 24. The forward portion of the receptacle is covered by a sheet metal cover-plate 72 pivoted to the receptacle by means of a screw 76 passing through the end of the arm 74 of the cover-plate. The opposite arm 78 of the cover-plate is arranged to engage beneath the thumb-nut 64 when the cover-plate is in closed position, 105 a notch 80 being formed in the arm 78 to receive the screw 66. The cover-plate is held in closed position by the tightening of the thumb-nut.

Having explained the nature and object 110 of the invention, and having specifically described a device embodying the invention in its preferred form, what is claimed is:

1. A thread-waxing device for applying melted wax to sewing thread, having, in 115 combination, a wax receptacle, a heating device, a support mounted on the heating device and arranged for rotatable adjustment thereon, and a thread guide mounted on the support.

2. A thread-waxing device for applying melted wax to sewing thread, having, in combination, a wax receptacle, a heating device arranged to extend into the receptacle, a support mounted on the heating device and 125 arranged for rotatable adjustment thereon, and a thread guide removably mounted on the support.

3. A thread-waxing device for applying melted wax to sewing thread, having, in 130

combination, a wax receptacle, a cover plate for the receptacle, a heating device arranged to extend into the wax receptacle, a thread guide carrier mounted on the cover plate, so

5 that it may be readily removed from the cover plate while the cover plate is in place on the receptacle, and arranged to extend downwardly into the receptacle alongside the heating device and a thread guide mounted on the lower end of the carrier.

10 4. A thread-waxing device for applying melted wax to sewing thread, having, in combination, a wax receptacle, a heating device arranged to extend into the wax in the 15 receptacle, a support rotatably adjustable on the heating device, a thread guide carrier removably mounted on the support and arranged to extend into the receptacle alongside the heating device, and a thread 20 guide mounted on the lower end of the carrier.

25 5. A thread waxing device for applying melted wax to sewing thread, having, in combination, a wax receptacle, means for heating the receptacle, a thread guide carrier arranged to extend into the receptacle, a thread guide mounted on the end of the carrier within the receptacle, and a sup-

port upon which the carrier is removably secured at its other end arranged for adjustment from a position in which the removal of the carrier is obstructed to a position in which the carrier may be readily removed.

30 6. A thread-waxing device for applying melted wax to sewing thread, having, in combination, a wax receptacle, means for heating the receptacle, a thread guide located within the receptacle for guiding the thread through the receptacle, and a support upon which the thread guide is carried arranged for rotatable adjustment to enable the thread guide to be readily removed from the receptacle.

35 7. A thread waxing device for applying melted wax to sewing thread, having, in combination, a wax receptacle, means for heating the receptacle, a cover plate for the receptacle, a thread guide carrier removably mounted on the cover plate and arranged to extend downwardly from the cover plate into the receptacle and upwardly beyond the cover plate to the outside of the receptacle, and a thread guide mounted on the lower end of the carrier.

40 50 ALFRED R. MORRILL.
